UNITED STATES PATENT OFFICE

JACOB BODENSTEIN, OF HERKIMER, NEW YORK

TYPEWRITER DESK

Application filed February 12, 1927. Serial No. 167,677.

This invention relates to improvements in typewriter desks of that kind having a typewriter platform on which a typewriting or other machine is supported, said platform being movable rearwardly and downwardly from its operative position to an inoperative position within the desk. A movable flat top or desk section covers the space over the typewriter when the latter is lowered, and link and lever or other connections are provided between said top and platform whereby the latter is raised when the desk top is lowered and vice versa. The invention is especially applicable to desks of this kind in which the platform moves from a substantially horizontal, operative position to an inclined inoperative position, extending downwardly and rearwardly, inwardly beyond the front of the desk to provide leg room for the user.

The objects of the invention are to provide an improved desk of the character described, having stop means whereby the machine platform and the desk top are positively arrested as they assume their respective operative and inoperative positions; also to provide means coacting with said stop means for rigidly locking or holding the machine platform in operative position; also to provide improved operative connections between the desk top and the platform for actuating the latter through movement of the former; also to provide guide and support means or parts of improved and simplified construction for guiding and supporting the platform when moving to and from operative and inoperative positions and supporting the same in such positions, and also to improve the construction of typewriter desks in the other respects hereinafter set forth.

In the accompanying drawings:

Fig. 1 is a longitudinal, sectional elevation of a typewriter desk embodying the invention, showing the machine platform in lowered or inoperative position.

Fig. 2 is a similar view with the platform in open or operative position.

Fig. 3 is a transverse, vertical section on an enlarged scale, of the connections between one end of the platform and the adjacent side

panel or stationary part of the desk, on line 3—3, Fig. 2.

Fig. 4 is a side elevation of the lever and link connections between the machine platform and the movable desk top or section, showing these parts in locking relation to the platform for holding the same rigidly in open position.

Fig. 5 is a side elevation of one of the fixed guide plates or members for guiding the platform in its movements to and from operative and inoperative position.

Fig. 6 is a similar view of one of a pair of supporting brackets on which are mounted the platform supporting studs or rollers and to which the connections between said platform and desk top are attached.

The desk in which the invention is used can be of any suitable construction adapted for use as a typewriter desk, or desk on which any other similar machine is mounted to move to and from operative or inoperative position in the manner described.

The desk shown in the drawings comprises the usual upright, opposed and spaced side panels, pedestals or members 10 rigidly connected at the rear by a vertical back wall 11, and also preferably by a fixed, horizontal rear top member 12. In front of the member 12 is a movable desk top or section 13, which in the position shown in Fig. 1 extends horizontally between the top edges or portions of the side members 10 and above a typewriter platform 14, which, in said position of the desk top, occupies a downwardly and rearwardly inclined or inoperative position.

The top section 13 has its rear ends pivoted to downwardly and forwardly extending links 16 which are connected at their lower ends to the adjacent side members 10 of the desk by pivots 17. By an upward and rearward movement of the front of the top section 13, said top, through its links 16, can swing about the pivots 17 to an upstanding position at the back of the desk in rear of the platform 14, with its rear edge preferably engaging suitable fixed rests or stops 18 on the side panels 10. This movement of the top 13 causes the platform 14 to move to its operative position shown in Fig. 2, through con-

nctions between said top and platform, in a well known manner.

In accordance with the present invention, said connections are constructed and arranged to coact with guides and stop means on the desk to support said platform and said desk top rigidly in their respective operative positions. For this purpose, the platform 14 is provided at each side with two laterally projecting spaced roller studs or followers 20 and 21. The studs 20 are arranged to travel in substantially horizontal slots or fixed guide ways 23, while the other studs 21 engage and travel in downwardly extending, preferably curved slots or guides 24. The guide ways or slots 23, 24 at opposite sides of the desk are disposed in planes extending from front to rear of the desk, and can be formed in the side panel 10, if desired. Preferably, however, said slots are formed in sheet metal brackets or stampings 25, having offset lugs 26 for securing them to the side panels 10 of the desk, see Fig. 5.

Stop means are provided against which the studs 20 and 21 can abut for positively arresting the movement of the platform as it assumes its operative position, said stops in the construction shown comprising the closed ends 27, 28 respectively of said slots 23 and 24.

Likewise, in the inoperative position of said platform, Fig. 1, these studs engage stops 29 and 30 comprising respectively the opposite ends of the slots 23 and 24. By the provision of the angularly related slots or guides 23, 24, disposed as shown, the platform is enabled to move from its horizontal, operative position to a downwardly and rearwardly inclined inoperative one, by the movement of the studs 21 along the depending slots 24, which causes a pivotal movement of the platform about the other studs 20, during the travel of the latter in said slots 23.

The operative connections between the platform 14 and top 13 comprises a link 31 connected at one end as by a pivot 32 to the front portion of the platform 14 and at its other end by a pivot 33 to one end of a lever 34 supported between its ends on the side wall or panel 10 by a stationary pivot 35 and having its opposite end pivoted in turn to the front portion of the desk top 13.

The drawings shown only the left hand side of the desk, but preferably similar link and lever mechanism is also arranged at the opposite side of the desk.

When the platform moves from its inclined position to its horizontal operative position, the pivot 33 passes slightly beyond a dead center position, or across a line connecting the stationary pivot 35 and the pivot 32 see Fig. 4. This relative arrangement and movement of the parts forms a lock joint and causes the rollers 20 and 21 to be forced and held firmly against the stops 27 and 28 respectively. By

this construction the platform is rigidly supported in horizontal operative position, and will not shift or become displaced under normal conditions of use, as the platform cannot be shifted except by lifting the desk top and breaking said lock joint.

If, however, the desk top is lifted upwardly and forwardly from its inoperative position, Fig. 2, the lever 34 will turn about its pivot 35 thus causing the pivotal connection between the same and the link 31 to pass back across said dead center line and break the lock joint. A continuation of the movement of the desk top to closed position will shift the rollers 20 rearwardly along the slots 23 and the rollers 21 downwardly in the slots 24 to the respective rear and lower ends of the slots where said rollers will rest against the stops 29 and 30. In this manner the platform is supported in inoperative position and the desk top is moved to and held securely in its desk closing position, Fig. 1. The front portion of the top is thus supported through the link and lever connections with the platform, while its rear portion is adequately supported by the links 16.

The studs or supporting rollers 20, 21 can be mounted on the platform in any suitable way, but each pair is preferably secured to a longitudinally extending flange 40 of a sheet metal stamping or supporting bracket 41, see Fig. 6. These brackets engage the respective adjacent edges of the platform and are attached to the platform by screws or other fastenings passing through horizontal flanges 42, 43 extending laterally from said brackets upon opposite faces of said platform. Each bracket 41 is also preferably provided with an upstanding lug 45 through which the pivot 32 for the link 31 passes.

Another important result obtained by the construction described is that the platform 14, while moving to its inclined, inoperative position, also moves rearwardly the length of the guides or slots 23 by reason of the studs 20 engaging therein, thus locating the inoperative position well back of the front edges of the side panels 10 and providing more knee space for the operator than is usually provided in desks of this type.

The supporting brackets 25 and attaching brackets 41 are inexpensive to produce and are strong and rugged, while the link and lever connections between the desk top and platform are simple and coact with the guide and supporting means to produce a desk construction wherein the platform and desk top are firmly held in their respective operative positions.

I claim as my invention:

1. In a typewriter desk, a frame having an opening in its top extending rearwardly from the forward edge, a closure for said opening carried by said frame for movement toward and from closed position in said open-

ing, a platform disposed in said frame below said opening, a horizontal guide on said frame at each side of said opening and extending in directions from front to rear, a second guide carried by said frame also at each side of said opening and at the rear of said horizontal guides, said second guides extending in directions crosswise of the horizontal guides and from adjacent the longitudinal axes of said horizontal guides downwardly and then rearwardly in an inclined direction, so that the guides at each side of the frame form an obtuse angle with one another at their outer ends and approximately a right angle at their adjacent ends, followers carried by said platform and cooperating with said guides to support the platform in an approximately horizontal position when the followers cooperating with the second guides are at the upper ends of those guides, and the followers co-operating when the horizontal guides are well forward on those guides, whereby said platform may be first tilted downwardly at its rear end and then the entire platform shifted rearwardly in said frame, and means connecting said closure to said platform, whereby movement of the closure into closed position causes a tilting of the platform and its rearward movement in the frame to increase the knee space.

2. In a typewriter desk, a frame having an opening in the top thereof, a platform disposed in said frame below said opening, guides carried by said frame at opposite sides thereof, and extending in directions from front to rear, additional guides at the rear of said first named guides and extending therefrom first in a direction crosswise of the length of the first mentioned guides and then rearwardly in a direction oblique to the first named guides, and followers carried by said platform and co-operating with each guide at each side of the frame for mounting the platform in a horizontal position when the followers co-operating with the additional guides are nearest the first named guides, and the followers of the first named guides are well in advance on said first named guides, whereby said platform may be tilted vertically at its rear end and then shifted bodily rearwardly in the frame, and means for moving the platform in either direction on said guides and locking it releasably in its approximately horizontal position.

3. In a typewriter desk, a frame having an opening in the top thereof, a platform disposed in said frame below said opening, guides carried by said frame at opposite sides thereof, and extending in directions from front to rear, additional guides at the rear of said first named guides and extending therefrom first in a direction crosswise of the length of the first mentioned guides and then rearwardly in a direction oblique to the first

named guides, and followers carried by said platform and co-operating with each guide at each side of the frame for mounting the platform in a horizontal position when the followers co-operating with the additional guides are nearest the first named guides, and the followers of the first named guides are well in advance on said first named guides, whereby said platform may be tilted vertically at its rear end and then shifted bodily rearwardly in the frame, a closure for said opening above the platform carried by said frame for movement between closed position in said opening and an approximately up-standing position within the rear of said frame, and means connecting said closure and said platform for holding said platform in horizontal position when said closure is in open position and moving said platform into inclined position and rearwardly in the frame when the closure is moved into closed position.

4. In a typewriter desk, a frame, a platform, a pair of followers at each side of said platform, the followers of each pair being spaced forwardly and rearwardly of one another, an approximately horizontal guide on said frame at each side of said platform and each guide having a pivotal and slidable connection with the adjacent forward follower, a second guide carried by said frame at each side of said platform and each having a pivotal and slidable connection with the adjacent rear follower, said second guide depending from adjacent the rear end of said horizontal guide and at its upper end extending crosswise of said horizontal guide, and then depending rearwardly in a direction oblique to the horizontal guide, the forward followers being at the forward ends of the horizontal guides when the rearward followers are at the upper ends of the second guides and with the platform approximately horizontal when said followers are so placed relatively to the guides, said platform having a pivot bearing spaced from one of the forward followers and laterally from the adjacent horizontal guide, a desk top mounted on said frame for movement between a closed position above said platform and an open position at the rear of said platform, said mounting including a lever pivoted to said frame, and a link connected to said lever and to said pivot bearing on said platform, the pivot of said lever being disposed rearwardly of said pivot bearing of said support, and said lever and link forming a toggle which slightly passes straightened position when said platform reaches its forward horizontal position and said top its open position, whereby said toggle connection will lock said platform in horizontal position when said top is in open position, and whereby movement of said top towards closed position will first break said toggle, rock said platform about its forward

120

125

130

followers, and then shift both followers along their guides to place said platform in an inclined position when said top is in closed position.

5. In a typewriter desk, a frame, a platform, approximately L-shaped brackets secured to said frame at opposite sides of said platform with one arm of each bracket extending approximately horizontally and forwardly, and the other arms of the brackets depending from the rear ends of the approximately horizontal arms and then rearwardly in a direction oblique to the forwardly extending arms, each arm of each bracket 10 having a slot running in a direction lengthwise therein, a pair of followers at each side of said platform spaced forwardly and rearwardly, the forward follower of each pair engaging in the slot of the horizontal arm and 15 the other follower of the same pair engaging in the slot of the depending arm, each follower providing a pivotal mounting for said platform, the upper ends of the slots in the depending arms being crosswise of the lengths 20 of the approximately horizontal arms, and the rear followers being in engagement with the upper ends of their slots when the forward followers are well forward in their slots. with the platform in horizontal position, said 25 platform having a bearing pivot spaced from the forward followers, a top mounted for swinging movement between a closed position above said platform, and an open position at the rear of the platform, the mounting 30 of the top including a lever, and a link connecting said lever and the bearing pivot of said platform and forming with said lever a toggle connection having a position slightly past dead center when said top is in open position 35 and moving through straightened position at the beginning of a closing movement of said top, the pivot of said lever being so spaced from said pivot bearing of the platform, when the platform is in horizontal position, that movements of the top in either direction between open and closed positions 40 will urge said platform forwardly or rearwardly in the frame.

6. In a typewriter desk, the combination of 50 a frame, a platform for supporting a typewriter or the like, a movable desk top, a lever pivoted between its ends to said frame, a pivotal connection between one end of said lever and said desk top, a link, a pivotal connection 55 between one end thereof and said platform, a pivotal connection between the other end of said link and the other end of said lever, a guide member on said desk frame having a substantially horizontal slot and a 60 second slot extending downwardly and rearwardly in angular relation thereto, a pair of spaced studs on said platform, one sliding lengthwise in each slot and supporting the platform for movement from inoperative to 65 operative position, a stop at the upper end of

the second slot against which the stud therein abuts for arresting the movement of said platform when it reaches its operative position, and said last-mentioned pivotal connection between said lever and said link being 70 movable across a dead center line between said lever pivot and the pivotal connection between said link and platform and then arrested by the engagement of a stud with said stop, whereby said top and platform counter-balance one another and said platform will be held securely in said operative position. 75
